(57) **CLAIM**

The ornamental design for a truck rack having replaceable decorative panels, as shown and described.

DESCRIPTION

FIG. 1 is a rear perspective view of the truck rack having replaceable decorative panels of our present invention with the dotted lines solely depicting environmental structure and forming no part of the claimed design;
FIG. 2 is a top plan view thereof;
FIG. 3 is a front elevational view thereof;
FIG. 4 is a left end elevational view thereof;
FIG. 5 is a right end elevational view thereof;
FIG. 6 is a bottom plan view thereof; and,
FIG. 7 is a rear elevational view thereof.
The truck rack is shown on an enlarged scale in FIGS. 2-7.
